UNITED STATES PATENT OFFICE.

JOSEPH P. GLASER, OF DETROIT, MICHIGAN, ASSIGNOR TO CHAMBERLIN METAL
WEATHER STRIP COMPANY, OF DETROIT, MICHIGAN.

WEATHER-STRIP.

1,379,915.

Specification of Letters Patent. Patented May 31, 1921.

Application filed September 27, 1917. Serial No. 192,624.

To all whom it may concern:

Be it known that I, JOSEPH P. GLASER, citizen of the United States, residing at 344 Hubbard Ave., Detroit, in the county of Wayne and State of Michigan, have invented certain new and useful Improvements in Weather-Strips, of which the following is a specification, reference being had therein to the accompanying drawing.

10 The invention relates to improvements in weather strips and more especially to devices of this character that are particularly adapted for casement windows and the like, and has for its object to provide an improved device of this nature of inexpensive, durable construction that will form an efficient seal or weather proof fitting.

The invention comprehends the provision of two coöperating metal strip members 20 applied to the sill of the casing or window frame and the bottom rail of the swinging member or sash. One of the metal strip members is constructed of resilient sheet metal and secured along one edge and free 25 at its opposite marginal portion for vertical movement, said member being provided with a resilient pocket at its free edge portion in which is adapted to fit a sealing tongue or portion of the other strip member when the swinging member is in closed 30 position. Normally the vertically movable strip member extends upwardly away from the frame or other part to which it is connected and is forced inwardly with its free 35 edge portion thereof in contact with said part when the swinging member is moved to closed position and the strip members engaged with each other.

An important novel characteristic of the 40 invention resides in the special formation of the resilient pocket of the vertically movable strip member whereby a very efficient sealing engagement of the strips is afforded, and also in the provision of a supplemental 45 sealing part in connection with the pocket of the vertically movable strip member, said supplemental sealing part acting to prevent the accumulation of dust, dirt, and the like, beneath the vertically movable strip 50 member that would prevent the proper functioning of the same, and serves as a protection for the pocket structure, an auxiliary barrier against the entrance of moisture,

air, etc., and also as a guide for maintaining the free edge portion of the strip in proper 55 working position.

The invention, with other objects and advantages thereof and the particular construction, combination and arrangement of parts comprising the same will be understood from the following detail description when considered in connection with the accompanying drawing forming part hereof and illustrating one embodiment of the invention.

In the drawing:

Figure 1 is a vertical section of a casement window provided with a weather strip constructed in accordance with the present invention, the window sash being in partly 70 open position with the strip members out of engagement;

Fig. 2 is a view similar to Fig. 1 with the window sash in closed position and the strip members in engagement; and

Fig. 3 is a detail perspective view of one of the strip members.

In the drawing is illustrated a preferred embodiment of the invention. It will of course be understood that minor changes 80 and modifications of the particular construction shown embraced within the scope of the appended claims may be made without departing from the spirit of the invention. The particular construction illustrated in the drawings comprises two metal strip members A—B, in the present instance connected respectively to the sill of the casing A' and to the bottom rail B' of the swinging member or sash.

The strip member A, which is constructed from a strip of resilient sheet metal has an attaching side marginal portion a' tacked or otherwise suitably secured to the sill A' of the casing at a². The strip is bent so that the main portion a³ thereof from the side marginal portion a' extends at an upward inclination away from the sill A' of the frame. At its outer free side edge portion the strip is bent to provide a pocket having 100 straight upper and lower walls a⁴—a⁵ extending parallel with each other and the face of the sill, and a curved or rounded portion a⁶ projecting downwardly below the pocket at the front thereof. From the outer 105 edge of the upper wall a⁵ of the pocket, the

strip is bent to provide the forwardly and downwardly extending portion a' , said portion extending from the front of the pocket back over and in front thereof and into the 5 groove c in the sill A' and adapted to have free vertical movement or play in said groove.

The other strip member B consists of a substantially flat plate or strip of metal, 10 said strip being tacked or otherwise suitably secured along one side marginal portion thereof to the bottom rail of the sash within a rabbet c' .

The sill strip A normally extends outwardly away from the face of the sill A' , as indicated in Fig. 1 of the drawing, the window sash being in open position. When the sash is moved to closed position the free edge portion b of the strip member B engages the upwardly inclined portion a^3 of the sill strip, forcing the same downward until the curved portion a^6 at the front of the pocket is pressed against the face of the sill. The free edge portion b enters the 20 pocket and fits tightly between the walls a^4-a^5 thereof, the special construction of said walls a^4-a^5 providing for an extended close fitting engagement between the edge portion b and each of the walls a^4-a^5 along 25 both the top and bottom faces of the edge portion b . When the portion a^3 of the sill strip is depressed, the portion a^7 at its free end, engages the front wall of the groove c and through its connection with the upper 30 wall a^5 of the pocket, functions to maintain the upper wall a^5 of the pocket in close engagement with the upper face of the portion b of the strip B. It will thus be seen that the particular construction of pocket, and 35 portion a^7 , co-acting therewith, provides a very efficient seal and weather proof fitting. In both the normal elevated position of the sill strip B and in its depressed position the forwardly and outwardly extending portion a^7 extends into the groove c in the sill. This portion a^7 acts to prevent the entrance 40 of dust or dirt beneath the sill strip and extending from the front of the pocket over and in front of the same serves to protect the pocket structure. It acts to support and 45 maintain the upper wall a^5 of the pocket in engagement with the upper face of the portion b of the strip B, and serves as an addi-

tional barrier against the entrance of moisture, air, etc.

What I claim is:

1. The combination with a casement window or the like, the sill of the casing being provided with a groove extending inwardly from the face thereof, of a weather strip comprising a strip member constructed from resilient sheet metal, the strip being secured along one side marginal portion to the sill of the casing, the strip from said marginal portion extending upwardly away from the face of the sill, said strip at its free edge portion being provided with a pocket, and with a portion connected with and extending forwardly from the upper wall of the pocket and downwardly around the pocket and 70 slidably fitting into the groove in the sill, and a second strip member secured to the bottom rail of the sash and provided with a sealing portion adapted to depress the upwardly extending portion of the other strip 75 member and to fit within the pocket of said strip member when the sash is moved to closed position.

2. The combination with a casement window or the like, the sill of the casing being provided with a groove extending inwardly from the face thereof, of a weather strip comprising a strip member constructed from a strip of resilient sheet metal, said strip being secured along one side marginal portion thereof to the sill of the casing, the strip from said marginal portion extending upwardly away from the face of the sill, said strip at its free edge portion being bent back upon itself to provide a pocket, and then bent forwardly and downwardly to provide a portion extending over, around and in front of said pocket, the forwardly and downwardly extending portion fitting within the groove in the sill, and a second strip member secured upon the bottom rail of the sash and having a sealing portion adapted to fit within the pocket of the other strip member when the sash is moved to closed position.

In testimony whereof I hereunto affix my signature in the presence of two witnesses.

JOSEPH P. GLASER.
